(57) **CLAIM**

The ornamental design for an electrosurgical electrode, as shown and described.

DESCRIPTION

FIG. 1 is a front perspective view of an electrosurgical electrode showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 4; and,

FIG. 9 is a cross-sectional view thereof taken through line 9-9 in FIG. 8.

The evenly-dashed broken lines in the figures depict portions of the electrosurgical electrode which form no part of the claimed design.

The dot-dash broken lines in the drawings depict the boundaries of the claim and form no part thereof.

The dot-dot-dash broken lines in the drawings depict the boundaries of the enlarged views that form no part of the claimed design.
